Inventor.

UNITED STATES PATENT OFFICE.

FRANÇOIS XAVIER POZNANSKI, OF PARIS, FRANCE.

FOUNTAIN-PEN.

SPECIFICATION forming part of Letters Patent No. 257,756, dated May 9, 1882.

Application filed November 30, 1881. (Model.) Patented in France June 20, 1881.

To all whom it may concern:

Be it known that I, F. X. POZNANSKI, of Paris, in the Republic of France, have invented an Improvement in Fountain-Pens, of which 5 the following is a specification.

The invention consists in adapting a pen-holder to receive and distribute ink by the particular means hereinafter described.

Figures 1 and 2 of the drawings are elevations, of which the former shows the exterior of the pen-holder and the latter that of the ink-bottle. Figs. 3 and 4 are vertical sections, exhibiting respectively the interior of the pen-holder and the ink-bottle.

15 In the drawings, *a* represents the main tube or ink-reservoir, having at the upper end a shouldered tube, *a'*, which supports an elastic top-closed tube or air-chamber, *b*.

c is a sleeve surrounding the end of the tube 20 *a'* and elastic tube *b* and piston-head *d*, and rests upon the upper edge of the reservoir-tube *a*, and has at the upper end an opening, *c'*, sufficiently large for the passage of the stem of piston *d*.

25 *e* is a hollow plug fitting the main tube *a*, closed at the lower end, and having near said end the side opening, *g*.

h is a rod bent at the lower end to form a right angle, and extending up loosely through 30 the center of plug *e* to the top of the reservoir-tube *a*. This facilitates the movement of the

air and the ink. *i* is an end-beveled tube which surrounds the lower part of tube *e* and projects beyond the tube *a*.

k is an ink-bottle having an elastic bottom, 35 *l*, and an elastic stopper, the top of the bottle also having a central hole, *m*, through which the tube *i* is entered. Then by pressing the elastic bottom upward a supply of ink is forced into the reservoir-tube *a*. The pen is inserted 40 in the usual way between the tubes *e* *i*, and is supplied, by a slight pressure with the piston upon the tube or air-chamber *b*, with ink enough to write several lines.

The ink-bottle which I preferably use in connection with the fountain-pen is described in order to make the invention more clearly understood, but will form the subject-matter of another application.

Having thus described all that is necessary 50 to a full understanding of my invention, what I claim as new is—

The combination of the piston *d*, elastic tube *b*, sleeve *c*, reservoir-tube *a*, having the shouldered end tube, *a'*, the hollow plug *e*, having closed bottom *f* and side opening, *g*, the rod 55 *h*, and the tube *i*, to form a pen-holder adapted to receive and distribute ink, as described.

FRANÇOIS XAVIER POZNANSKI.
